UNITED STATES PATENT OFFICE.

MARCUS A. LOUER, IRA S. REIS, AND CHARLES CONRADT, OF PHILADELPHIA,
PENNSYLVANIA.

DESIGN FOR A CIGAR-LIGHTER STAND.

SPECIFICATION forming part of **Design No. 25,766**, dated July 7, 1896.

Application filed May 2, 1896. Serial No. 590,033. Term of patent 3¹ years.

To all whom it may concern:

Be it known that we, MARCUS A. LOUER, IRA S. REIS, and CHARLES CONRADT, residing at Philadelphia, in the county of Philadelphia and State of Pennsylvania, have invented and produced a new and original Design for Cigar-Lighter Stands, of which the following is a specification, reference being had to the accompanying drawing, forming a part thereof.

The accompanying drawing is a view in side elevation of our cigar-lighter stand.

The leading feature of our design consists in the bell-shaped base portion, having an ornamental exterior, and the tulip, the tulip-stem, and leaves thereon.

A represents the body portion of the outfit. This has the general form of a bell. It is ornamented with the leaves *b*, the stems *c*,

and blossoms *d*, and across its front a streamer *e* may be gracefully festooned to receive the owner's or manufacturer's name. At the upper end of the body portion the beadwork *f* is formed. On top a plate or disk *g* is placed, and out of the top a tulip *h*, stem *i*, and leaves *j* extend, so that the whole really presents the appearance of a flower and jardiniere.

What we claim as new, and desire to secure by Letters Patent, is—

The design for a cigar-lighter stand herein shown and described.

MARCUS A. LOUER,
IRA S. REIS,
CHAS. CONRADT.
